UNITED STATES PATENT OFFICE.

JOHN HAM, OF BROOKLYN, NEW YORK, ASSIGNOR TO THE HAM COAL SAVING COMPANY, OF NEW YORK, N. Y.

BOILER-FURNACE.

SPECIFICATION forming part of Letters Patent No. 354,057, dated December 7, 1886.

Application filed April 15, 1886. Serial No. 199,018. (No model.)

To all whom it may concern:

Be it known that I, JOHN HAM, a citizen of the United States, residing at Brooklyn, in the county of Kings and State of New York, 5 have invented new and useful Improvements in Boiler-Furnaces, of which the following is a specification.

This invention has for its object to provide a novel device for supplying heated air to 10 air-distributors situated in the fire-chamber above the grate-bars, the construction of said device being pointed out in the following specification and claims, and illustrated in the accompanying drawings, in which—

15 Figure 1 represents a sectional front view. Fig. 2 is a sectional side view in the plane xx , Fig. 1. Fig. 3 is a horizontal section in the plane yy , Fig. 2.

Similar letters indicate corresponding parts. 20 In the drawings, the letter A designates a steam-boiler extending over the fire-chamber B and combustion-chamber C. The products of combustion pass, as indicated by the arrow in Fig. 2, from the fire-chamber through the 25 flue-passage D, over the bridge-wall E, through the combustion-chamber to the rear of the boiler, thence through the boiler-flues F into the uptake-flue G, and thence through the connecting uptake-pipe H into the smoke-flue I, and thence to the chimney. (Not shown.) The flue I extends above the boiler, 30 and may serve as the flue to two or more fire-chambers or furnaces, if desired. In this example two furnaces, each with its steam-boiler, 35 are shown with the flue I arranged above.

Upon one side of the discharge-flue I is a chamber, J, formed in this example by riveting to the flue the flaring edges of a plate bent outward so as to form an air space or 40 chamber, J, between it and the side of the flue. The left-hand end of the flue I is closed, as is the left hand of the chamber J. The chamber J extends nearly to the other end of the flue I, and its right-hand end is open 45 to admit the entrance into it of the atmospheric air, which passes through it to the connecting-pipe K, and through it to the return hot-air pipe L, which extends along the front 50 of the air-chamber J nearly to its open end, or as far as the furnaces extend in that direc-

tion. The hot-air pipe L is closed at both ends, and from it extend pipes M, which conduct the hot air from it down into air-distributors N, arranged in the fire-chamber or in the walls of the fire-chambers.

The air-distributors consist of boxes arranged in the fire-chambers, preferably in the side walls, extending from the front as far as or nearly to the bridge-walls, and perforated on the inner side, or the side nearest to the grate, with numerous holes, through which the hot air discharged into them through the air-pipes M is distributed and discharged into the fire-chamber.

By the means above described the products 65 of combustion which pass into the flue I are used to heat the air which passes through the air-chamber J, so that when the current of air which enters that chamber at its right-hand end reaches its other end and passes 70 through the connecting-pipe K into the pipe L it will have become more or less heated, and consequently is in a favorable condition as to 75 temperature for being discharged into the furnace through the distributing-pipes M and the perforated distributing-boxes N. The operations of the furnace are thus facilitated, and a more perfect combustion of the fuel and an increased production of steam obtained 80 than has been heretofore realized in boiler-furnaces of this description, and these results are reached without arresting the discharge of the products of combustion or injuriously interfering with the construction or proper operation of the apparatus.

What I claim as new, and desire to secure by Letters Patent, is—

1. The combination, with a boiler-furnace, and with air-distributors situated in the fire-chamber thereof above the grate bars, of an 90 air-heating chamber formed on the smoke-flue and open at one end and closed at its opposite end, a hot-air pipe which opens into the air-heating chamber, near the closed end thereof, and branch pipes leading from the 95 hot-air pipe to the air-distributors, substantially as shown and described.

2. The combination, with a boiler-furnace, and with air-distributors situated in the side walls of the fire-chamber above the level of 100

the fire-grate, of an air-heating chamber formed on the smoke-flue and open at one end and closed at its opposite end, a hot-air pipe opening into the air-heating chamber near its closed 5 end, and branch pipes leading from the hot-air pipe to the air-distributer, substantially as shown and described.

In testimony whereof I have hereunto set my hand and seal in the presence of two subscribing witnesses.

JOHN HAM. [L. S.]
